UNITED STATES PATENT OFFICE.

WILLIAM GOLDIE, OF WILKINSBURG, PENNSYLVANIA.

RAILROAD COMPOSITE TIE.

No. 816,977.

Specification of Letters Patent.

Patented April 8, 1908.

Application filed December 5, 1903. Serial No. 183,969.

To all whom it may concern:

Be it known that I, WILLIAM GOLDIE, a resident of Wilkinsburg, in the county of Allegheny and State of Pennsylvania, have invented a new and useful Improvement in Composite Railroad-Ties; and I do hereby declare the following to be a full, clear, and exact description thereof.

My invention relates to composite metal and wood railway-ties; and its object is to provide a tie of this character which is practically indestructible by the elements, which does not destroy the insulation of the rails, so that the latter can be used for signaling and other purposes, and which will hold the spikes more securely than ordinary wooden ties.

Composite metal and wooden ties have heretofore been made, these comprising in their general construction a hollow box-like metallic body provided with openings in its upper face and having blocks of wood inserted in said box underneath the openings, to which blocks of wood the rails are spiked. In prior devices of this kind, as far as I know, the holes through the top face of the box-like metallic member were of such a size that the rail or its fastening means contacted with some portion of the metallic tie member. The difficulty with this construction is that each tie forms a metallic cross connection between the rails, thus entirely destroying their value as conductors for signaling and similar purposes. Furthermore, in prior ties of this kind, as far as I know, the wooden blocks are just as liable to decay and have no better gripping power on the spikes than the ordinary wooden ties.

The object of my invention is to improve composite metal and wooden railway-ties so as to overcome the several defects above noted. To this end the invention consists, generally stated, in a tie having a hollow or tubular metallic body provided with openings in its top surface, together with wooden spike-receiving blocks inserted into said hollow body underneath said openings, the openings being of considerable size, and the side walls of the hollow body being also cut away at said openings, so that the rails rest entirely upon the wooden blocks and are not in contact with any part of the metal body portion of the tie, so that the insulation of the rails is not destroyed and their use for signaling and similar purposes is fully preserved.

The invention also consists in treating the

wooden blocks prior to their insertion into the hollow body with some wood-preserved, such as sulfate of zinc, which will preserve the same from decay and render it practically indestructible except by mechanical forces.

The invention also consists in compressing or compacting the wooden blocks and forcing them in compressed condition into the tubular body, thus rendering the fiber of said blocks more dense and greatly increasing the holding power on the spikes.

In the accompanying drawings, Figure 1 is a perspective view of one form of my improved tie. Figs. 2 and 3 are similar views of other forms thereof. Fig. 4 is a longitudinal vertical section through the tie shown in Fig. 1. Fig. 5 is a diagrammatic view illustrating the treatment of the wooden blocks with a wood-preserved, and Fig. 6 is a longitudinal section through suitable apparatus for compressing the blocks and forcing the same into the tubular metallic body.

My improved tie will have a hollow metallic body 1, which may be of various constructions and forms, but which preferably will be a metallic tube flattened on two sides at its ends at least to form flat top and bottom surfaces. The side edges also may be flattened, if desired; but to facilitate tamping the ballast in place I prefer to leave them rounded, as shown in the drawings. This tube may have the flattened top and bottom surfaces extend for its whole length, as shown in Fig. 1, or said flattened faces may be only at the ends, as shown in Fig. 2, or the top surface may be flat for the full length, while the bottom surface is flattened only at the ends, as shown in Fig. 3. The top surface should be flattened at the ends to give a good rail-seat, while the lower surface should be flattened at the ends to give a good bearing on the ballast, and preferably said lower face will be left rounded intermediate the ends, as in Figs. 2 and 3, so it will work down into the ballast, and thus prevent center binding.

The tubular body 1 is provided near opposite ends thereof with an opening 2, cut through the top thereof. The side walls are also cut away, as at 3, at these openings. Into this tube underneath the openings 2 I insert wooden blocks 4, whose upper face naturally projects above the top edge of the side walls of the tube at the openings, and the openings 2 are of such size that when the rail

5 is in place it will be supported entirely on the wooden block and neither said rails nor the spikes will be in contact with any portion of the metallic part of the tie. In this manner the rails are thoroughly insulated and their use for signaling and other purposes fully preserved. In cases where traffic is severe tie-plates of any approved form may be used between the base of the rail and the tie; but in such cases care must be taken to so place the tie-plate that it will not contact with the metallic body 1, as otherwise the insulation of the rail would be destroyed.

The rails 5 are secured to the wooden blocks by the usual spikes 7, and in order to increase the grip of the blocks on the spikes said blocks are compressed very firmly before being inserted into the tubular body. This may be accomplished by any suitable apparatus—such, for instance, as presses of various forms. Preferably, however, a funnel or tapered guide 8 is employed. The tubular body 1 is held rigidly in place at the small end of the funnel, and the block is then forced by any suitable means, such as the plunger 9, through the funnel and into the tube. The funnel is of such length and taper that by the mere act of forcing the block through the same it will be very firmly compressed, said block preferably being first steamed, so as to render it yielding. A block of sufficient size is taken, so that when compressed it will fit very securely in the tube 1, and as it is forced into said tube in this compressed state it will be held therein with sufficient friction to prevent movement therein. If desired, resort may be had to a bolt or other holding means, such as pressing the walls of the tube inward behind the block. The method of making the tie disclosed herein is not claimed in this application, but is claimed in my application, Serial No. 183,968, filed concurrently herewith. In this manner the fibers of the blocks 4 become very close and dense, being retained in this condition by the fact that they fit very closely in the tube 1. They therefore will very firmly grip the spikes driven into the same. The density of the wooden blocks also considerably increases the life of said blocks, due to the fact that moisture will not easily penetrate the same. To increase their life, however, said blocks are treated before being compressed by any well-known wood-preservative, such as sulfate of zinc, this treatment being given to the blocks in any suitable or desirable way, such as immersing the same in a tank 15, containing a solution of the wood-preservative, which will thus impregnate the blocks. The compressing of the blocks after treatment with the wood-preservative closes up the cellular tissues and binds the chemical in the wood and solidifies the same to such a degree that it cannot be dissipated either by leaching or evaporation.

It will thus be seen that my composite tie is practically indestructible by ordinary chemical actions of the elements and that the life of the wooden parts will be practically the same as that of the metallic parts. This tie offers a very firm base for the rail and a very secure holding means for the spikes. For all intents and purposes also it has all the benefits of a wooden tie, thoroughly insulating the rails and making it possible to use the ordinary signaling systems in connection therewith. Only a small portion of the tie is of wood, while the treatment of the wooden blocks with a preservative and afterward compressing the same makes it possible to use soft, cheap, and otherwise useless wood, such as pine, cotton-wood, and the like, important considerations by reason of the coming scarcity of wood for tie purposes.

As weight is an essential or at least a desirable element of railway-ties, the central tubular portion between the wooden blocks may be filled with sand, cement, or other suitable material 16, and the end portions outside of the wooden blocks may also be filled with cement or other suitable material 17.

In place of the wooden blocks I may use blocks of wood-pulp, waste leather, felt, or other suitable fiber suitably compressed to sufficient density to hold the spikes and also acting as insulation.

What I claim is—

1. A railway-tie comprising a tubular metallic body and rail-supporting blocks of insulating material secured to said body in such manner as to support the rail and its fastening means out of contact with all parts of the metal body.

2. A railway-tie comprising a metallic hollow body having openings in its upper surface near its ends, said openings being of sufficient size to prevent the rail and its fastening means from contacting with any portion of the metallic tie-body, and rail-supporting blocks of insulating material in said body opposite said openings with their upper surfaces projecting above the sides of the openings in the metallic body.

3. A railway-tie comprising a tubular metallic body having openings in its upper face near each end, said openings extending down into the side walls of the body and being of sufficient size to prevent the rail or its fastening means from contacting with any portion of the metallic tie-body, and rail-supporting blocks of insulating material in said body underneath said openings with their upper faces above the tops of the side walls at the openings.

4. A railway-tie comprising a metallic tube flattened on its top and bottom faces at its ends at least and having openings in its upper face near each end, said openings extending down into the walls of the tube and being of

- sufficient size to prevent the rail or its fastening means from contacting with any portion of the metallic tie-body, and rail-supporting blocks of insulating material in said body underneath said openings with their upper faces above the tops of the side walls at the openings.
5. A railway-tie comprising a hollow metallic body having openings in its upper face near each end, and rail-supporting and spike-receiving blocks consisting of fiber compressed to a density sufficient to hold spikes and being placed in said hollow body underneath said openings.
10. 6. A railway-tie comprising a hollow metallic body having openings in its upper face near each end, said openings extending down into the side walls of said hollow body, and rail-supporting and spike-receiving blocks
15. consisting of fiber compressed to a density sufficient to hold spikes and being placed in said body underneath said openings with their upper faces above the top of the side walls of the hollow body at the openings.
20. 7. A railway-tie comprising a metallic body consisting of a tube having flattened top and bottom faces at its ends at least and having openings formed in its top face near its ends, said openings extending down into
25. the side walls of the tube, and rail-supporting and spike-receiving blocks consisting of compressed wood inserted in said tube underneath said openings with their upper faces above the top edges of the side walls of the tube at the openings.
30. 8. A railway-tie having spike-receiving portions of fiber compressed to a density sufficient to hold spikes and means for holding the same in compressed condition.
35. 9. A railway-tie comprising a metallic body, and spike-receiving portions consisting of fiber compressed to a density sufficient to

hold spikes and suitably secured to said body.

10. A railway-tie comprising spike-receiving portions of compressed chemically-treated wood, and means for holding the same in compressed condition.

11. A railway-tie comprising a hollow metallic body having openings in its upper face near its ends, and spike-receiving blocks of compressed chemically-treated wood inserted in said body opposite said openings.

12. A railway-tie comprising a hollow metallic body having openings in its upper face near each end, said openings extending down into the side sills of said tube, and spike-receiving blocks of compressed chemically-treated wood placed in said body opposite said holes with their upper faces bearing against the top of said tube.

13. A railway-tie comprising a hollow metallic body having its lower face flattened at the ends and the intermediate portion round, said body having openings in its upper face, and spike-receiving blocks in said body opposite said openings.

14. A railway-tie comprising a body having its lower face flattened transversely at the ends and the intermediate portion convex.

15. A railway-tie comprising a metallic tube flattened at its ends at least and having openings cut in its upper face, and spike-receiving blocks of chemically-treated fibrous material compressed to a density sufficient to hold spikes and positioned in said tube opposite said holes.

In testimony whereof I, the said WILLIAM GOLDIE, have hereunto set my hand.

WILLIAM GOLDIE.
